(57) **CLAIM**

The ornamental design for a coil for medical imaging apparatus as shown and described.

DESCRIPTION

FIG. 1 is a front view of a coil for medical imaging apparatus showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof; and,

FIG. 7 is a top, front, left-hand side perspective view thereof.
